UNITED STATES PATENT OFFICE.

WILLIAM GEORGE WILLI, OF SACRAMENTO, CALIFORNIA.

DESIGN FOR A BOOK-HOLDER, &c.

SPECIFICATION forming part of Design No. 22,869, dated November 7, 1893.

Application filed February 4, 1893. Serial No. 461,068. Term of patent 3½ years.

To all whom it may concern:

Be it known that I, WILLIAM GEORGE WILLI, of Sacramento, in the county of Sacramento and State of California, have invented and produced a new and original Design 5 for Book or Music Holders; and I do hereby declare the following to be a full, clear, and exact description of the invention, such as will enable others skilled in the art to which it appertains to make and use the same.

This invention relates to a design for a book or music holder, which will be more fully hereinafter referred to.

The accompanying drawing represents a 15 perspective view of my new and original design.

The leading features of the design consist of a rectangle A, comprising a series of loops or grooves B arranged on the diagonals of 20 the said rectangle, and at the corners of the rectangle, are circles C. Projecting from the

back of the rectangle are converging angles D meeting in a cylinder E, from which extends a gracefully curved support F. Harmonizing with the rectangle A, are projections G, arranged in straight and curved lines, which are coiled at the points H, while at the center of the said rectangle is an elongated loop J extending transversely, and having one end tapered and slightly curved. 25 30

Having thus described the invention, what is claimed as new is—

The design for a book or music holder, as herein shown and described.

In testimony whereof I have signed this 35 specification in the presence of two subscribing witnesses.

WILLIAM GEORGE WILLI.
